(57) **CLAIM**

The ornamental design for a curved canopy bed headboard, as shown and described.

DESCRIPTION

FIG. 1 is a top perspective view of a curved canopy bed headboard showing my new design;

FIG. 2 is a bottom perspective view thereof;

FIG. 3 is a front view thereof;

FIG. 4 is a back view thereof;

FIG. 5 is a top view thereof;

FIG. 6 is a bottom view thereof;

FIG. 7 is a left view thereof;

FIG. 8 is a right view thereof; and,

FIG. 9 is a top perspective view thereof.

The broken lines showing of orifices in FIG. 1 and FIG. 9, the broken lines showing of drawers in FIG. 1-3 and FIG. 5-9, and the broken lines showing of a bed in FIG. 10 are included for the purpose of showing environmental structure and form no part of the claimed design.
